UNITED STATES PATENT OFFICE

WALTER D. TEAGUE, OF FOREST HILLS, NEW YORK

DESIGN FOR A JAR OR SIMILAR CONTAINER

Application filed May 19, 1930. Serial No. 35,688. Term of patent 3½ years.

To all whom it may concern:

Be it known that I, WALTER D. TEAGUE, a citizen of the United States, residing at Forest Hills, in the county of Queens and State of New York, have invented a new, original, and ornamental Design for a Jar or Similar Container, of which the following is a specification, reference being had to the accompanying drawing, forming part thereof.

Fig. 1 is a horizontal section, looking down, taken substantially on the line 1—1 of Fig. 2.

Fig. 2 is an elevation of a container showing my new design.

Fig. 3 is the bottom plan of the container as shown in Figure 2.

I claim:

The ornamental design for a jar or similar container as shown.

WALTER D. TEAGUE.
